United States Patent Office.

WILLIAM H. HUMPHREY, OF LANSINGBURG, NEW YORK.

Design No. 4,144, dated June 7, 1870.

DESIGN FOR TILES.

The Schedule referred to in these Letters Patent and making part of the same

To all whom it may concern:

Be it known that I, WILLIAM H. HUMPHREY, of Lansingburg, in the county of Rensselaer and State of New York, have invented certain new and useful Improvements in Design for Tiles; and I do hereby declare that the following is a full, clear, and exact description thereof, reference being had to the accompanying drawings, and to the letters of reference marked thereon, which form a part of this specification.

My design for a tile consists of a scalloped piece of wood or iron, with an enlarged base, and provided on

one side with projections *a a*, for the purpose of holding the tile more securely in the ground.

What I claim, and desire to secure by Letters Patent, is—

The design for the tile, as described and shown in the accompanying drawings.

In testimony that I claim the foregoing as my own, I affix my signature in presence of two witnesses.

WM. H. HUMPHREY.
